UNITED STATES PATENT OFFICE.

EDGAR RUSSEL, OF THE UNITED STATES ARMY.

FLASH-LIGHT PHOTOGRAPHY.

No. 853,035.

Specification of Letters Patent.

Patented May 7, 1907.

Application filed July 26, 1906. Serial No. 327,701.

To all whom it may concern:

Be it known that I, EDGAR RUSSEL, major Signal Corps, United States Army, and a citizen of the United States, residing at Washington, in the District of Columbia, have invented certain new and useful Improvements in Flash-Light Photography; and I do hereby declare the following to be a full, clear, and exact description of the invention, such as will enable others skilled in the art to which it appertains to make and use the same.

My invention relates to improvements in flash light apparatus for use with photographic cameras, and it consists in providing certain improved apparatus wherein a number of flashes may be made in the same room without vitiating the air, and in which the flash is produced instantaneously, when desired, and without any hang-fires.

Furthermore in the hereinafter described apparatus the flash light is diffused, and the smoke fumes are retained in the apparatus.

According to my invention the powder for the flash light is contained in a convenient cartridge and is ignited by an electric spark.

Furthermore, the apparatus is adapted to be readily assembled or taken apart for transportation from place to place, as may be desired.

My invention will be understood by reference to the accompanying drawings, in which the same parts are indicated by the same letters throughout the several views.

Figure 1 is a side elevation showing the complete apparatus mounted and ready for use. Fig. 2 shows the extensible stand folded in shape for transportation. Fig. 3 shows a central vertical section of the pyramidal chamber, in which the flash light powder is burned. Fig. 4 shows the combined holder and igniter for the cartridge, parts being broken away. Fig. 5 is a plan view of the head of the holder and igniter with the cartridge removed. Fig. 6 is a detail showing the insulating cap used for holding the cartridge, as detached from the apparatus. Fig. 7 shows a section through the cartridge, and Fig. 8 is a plan view of the cartridge.

A represents a frame having folding legs A' pivoted as at a to the sleeve A⁰. These legs A' are connected by the links B to the collar C secured to the end of the hollow post C', which passes through the sleeve A⁰ and is clamped in the desired position by means of the clamp screw a'. This hollow sleeve is provided with a clamp C² and clamp

screw c to engage the post D, which passes down through the hollow post C. This post carries at its upper end a clutch member E adapted to engage the corresponding clutch member E' carried by the pyramidal box F. By means of the clamp nut E² and the screw e, this pyramidal box may be adjusted at any desired angle, while the height of the box may be varied by means of the clamp screws a' and c. This box F is provided with a block f at its apex, to which the member E' of the clutch coupling is attached. The box is formed of two parts F' and F² stiffened by the ribs f', f⁰ and f². The part F' of the box is made of sheet metal, preferably tin, while the part F² is covered with translucent material, which is not particularly inflammable, such as tracing linen.

The outer end of the box is closed with a door F³, which comprises a square frame f³ with tracing linen f⁶ stretched across it. This door frame f³ is hinged preferably to the bottom of the box, as at f⁴, and is normally locked in place by one or more hooks f⁵.

H represents a socket for the cartridge holder and igniter, which socket is permanently secured in the bottom of the box F and is provided with a curved slot h in its side, which is adapted to receive the pin k⁰, see Fig. 4, of the cartridge holder K, and secures same in place, after the manner of a bayonet joint.

The holder K is preferably made of two parts, the main body K' being of wood, to which is secured the binding posts k, and through which pass the wires k'. The other member is preferably in the form of a cup-shaped cap K² made of slate, porcelain, or other suitable insulating material, secured to the wooden block K', by means of the screws k⁴. This cap K² is cupped, as at k², to receive the cartridge M. The bottom of the cup is recessed, as at k⁵, see Fig. 6, to receive the bent-over ends of the wires k'. Between these recesses k⁵ there is a short bridge of insulating material k³.

The cartridge M is preferably made by stamping out a ring m of cardboard, or other insulating material, of sufficient thickness, then pasting over one side of this ring a paper disk m', filling the cup formed in the interior of the ring with the flash light powder m³, and then pasting on a strip of thin paper m² to form the top of the cartridge.

The binding posts k are connected by a suitable cable N to any suitable source of

electricity, such, for instance, as the induction coil *P*, which derives its electricity from the battery *Q*. This battery may be conveniently supported on a table *R*, suspended by hooks *r* from the links *B*, as shown in Fig. 1. The induction coil *P* may be connected to the frame of the apparatus, as by means of the clamps *p*.

- The operation of the device is as follows.
- 10 The box *F* being adjusted to the proper height by means of the clamps *a'* and *c*, and being tilted through the proper angle, and clamped by means of the clamp *E*², the cartridge holder *K* is detached from the box, a
  - 15 cartridge is inserted in the cup *k*², and the holder *K* is restored to the initial position. It will be seen that the bottom of the cartridge will be separated from the terminals of the wires *k'* by the thickness of the paper, and by a thin film of air, and thus the powder will be insulated from the wires *k'*. Now, if the push button *N'*, see Fig. 1, be pressed, the electric spark will jump across the gap above the bridge *k*³, penetrating the paper bottom *m'* of the cartridge, and setting fire to the powder *m*³. Thus it will be seen that instantaneous and thoroughly reliable action is had without the occurrence of any of the hang-fires which are so seriously objectionable in flash light photography.
  - 20 The light from the burning powder will be diffused through the translucent material *f*⁶, and the solid deposit from the products of combustion will whiten the interior of the part *F'* of the box, tending to increase the reflection therefrom.
  - 25

It will be obvious that the apparatus may be used over and over again by simply taking out the holder *K* and putting in a fresh cartridge, and that the escape of smoke and gases through the socket *H* during the brief time when open will be comparatively insignificant.

When it is desired to get rid of the smoke and gases inclosed in the box *F*, it may be removed from the top of the stand and carried to a window, and the door *F'* may be opened to the outer air. This door also affords convenient access to the interior of the box for cleaning or for other purposes.

For convenience in transportation, the case *P* containing the coil may be removed, as also the cells *Q* and the table *R*, the box *F* may be detached from the top of the stand, and the stand may be folded up, as shown in Fig. 2. The box itself may be made to knock down and fold up flat.

By having the powder arranged in the form of cartridges, as described, it may be conveniently transported and quickly used without the necessity of measuring out same before each use. Moreover, by varying the chamber for the powder in the cartridge, which may be done by either thickening the axial diameter of the ring *m*, or decreasing

the radial thickness of said ring, various charges of powder may be used without increasing the width of the cartridge. Thus a stock of cartridges containing different amounts of powder can be quickly and conveniently made up, which can be used later when occasion requires.

It will be obvious that various modifications in the herein described apparatus may be made, which can be used without departing from the spirit of my invention.

Having thus described my invention, what I claim and desire to secure by Letters Patent of the United States, is:—

1. A flash light apparatus comprising an adjustable stand, a pyramidal box carried by said stand and having its base and the adjacent portions of its sides composed of a skeleton frame covered with translucent material, a detachable cartridge holder adapted to project into said box and provided with electric terminals for forming an arc, and means for causing an electric spark to jump across said terminals and pierce the cartridge thus igniting the powder, substantially as described.

2. A flash light apparatus comprising a stand, a pyramidal box carried by said stand and having its base and portions of its sides made of translucent material, a detachable cartridge holder adapted to project into said box and provided with a cartridge holding cup, with electric terminals separated by an insulating bridge and embedded in the bottom of said cup, and means for causing an electric spark to pass over said bridge and pierce the cartridge held in said cup, thus igniting the powder, substantially as described.

3. A flash light apparatus comprising a portable stand, a tapered box adjustably connected to said stand and having a skeleton base covered with translucent material, a cartridge holder detachably connected to and adapted to project into said box and provided with electric terminals for forming an arc, a cartridge mounted in said holder and provided with a thin perforable bottom, and means for causing an electric spark to jump across said terminals and pierce the bottom of the cartridge thus igniting the powder, substantially as described.

4. A flash light apparatus comprising an adjustable stand, a pyramidal box carried by said stand and having a skeleton base covered with translucent material, a detachable cartridge holder adapted to project into said box and provided with electric terminals separated by an insulating bridge, a cartridge mounted in said holder and provided with a thin perforable bottom, and means for causing an electric spark to pass over said bridge and pierce the cartridge thus igniting the powder, substantially as described.

5. A flash light apparatus comprising an adjustable stand, a pyramidal box carried by

said stand and having its base and the adjacent portions of its sides composed of a skeleton frame covered with translucent material, a detachable cartridge holder adapted to project into said box and provided with electric terminals for forming an arc, a cartridge mounted in said holder and provided with a thin perforable bottom, and means for causing an electric spark to jump across said terminals and pierce the cartridge thus igniting the powder, substantially as described.

6. A flash light apparatus comprising a stand, a pyramidal box carried by said stand and having its base and portions of its sides made of translucent material, a detachable cartridge holder adapted to project into said box and provided with a cartridge holding cup, with electric terminals separated by an insulating bridge and embedded in the bottom of said cup, a cartridge mounted in said holder and provided with a thin perforable bottom, and means for causing an electric spark to pass over said bridge and pierce the cartridge held in said cup, thus igniting the powder, substantially as described.

7. A flash light apparatus comprising an adjustable stand, a box carried by said stand and having its base made mainly of translucent material, a detachable cartridge holder adapted to project into said box and provided with electric terminals separated by an insulating bridge, a cartridge mounted in said holder and provided with a thin perforable bottom, and means for causing an electric spark to pass over said bridge and to pierce the cartridge igniting the powder, substantially as described.

8. A flash light apparatus comprising a portable and adjustable stand, a pyramidal box adjustably mounted on said stand and having its base and portions of its sides made of translucent material, a detachable cartridge holder adapted to project into said box and provided with a cartridge holding cup, with electric terminals separated by an insulating bridge and embedded in the bottom of said cup, a cartridge mounted in said cup, and means for causing an electric spark to pass over said bridge and pierce the cartridge held in said cup, thus igniting the powder, substantially as described.

9. In a flash light apparatus comprising a stand, a box adjustably connected to the top of said stand, parts of said box being covered with translucent material, a cartridge holder adapted to project into and to be detachably connected to said box, a cartridge mounted in said holder, electric conductors carried by said holder and forming a gap in juxtaposition to said cartridge, a source of electricity

and means for completing the circuit through said conductors and thus forming a spark at said gap, substantially as described.

10. A flash light apparatus comprising a stand, a tapered box adjustably connected to the top of said stand, parts of said box being covered with translucent material, a cartridge holder adapted to project into and to be detachably connected to said box, a cartridge mounted in said holder, electric conductors carried by said holder and forming a gap in juxtaposition to said cartridge, an electric battery carried by said stand, an induction coil also carried by said stand and connected to said battery, electric conductors connecting said induction coil and said cartridge holder, and means for completing the circuit through said conductors and thus forming a spark at said gap, substantially as described.

11. A flash light apparatus comprising a portable and vertically adjustable stand, a pyramidal box having its apex adjustably connected to the top of said stand, the base and adjacent parts of said pyramid being covered with translucent material, a cartridge holder adapted to project into and to be detachably connected to the said box, a cartridge mounted in said holder, electric conductors carried by said holder and forming a gap in juxtaposition to said cartridge, an electric battery carried by said stand, an induction coil also carried by said stand and connected to said battery, electric conductors connecting said induction coil and said cartridge holder, and means for completing the circuit through said conductors and thus forming a spark at said gap, substantially as described.

12. A cartridge for use in flash light apparatus comprising a disk of cardboard or other suitable material cut away at its center to form a powder chamber, an upper and lower disk secured to said cardboard disk, and powder held in the chamber thus formed, substantially as described.

13. A cartridge for use in flash light apparatus comprising a body portion made of cardboard or the like, cut away in the center to form a powder chamber, and thin sheets of paper pasted over the top and bottom of said body portion and inclosing the powder, substantially as described.

In testimony whereof, I affix my signature, in presence of two witnesses.

EDGAR RUSSEL.
